A technical drawing of a mechanical assembly, possibly a lock or fastener. The drawing shows a central vertical component with a rectangular base. Various parts are labeled with numbers: 29, 31, 34, 28, 27, 26, 21, 38, and 22. A date stamp '20/1/19' is visible at the bottom. The entire drawing is enclosed in a rectangular border.

SHUTTLE

Application filed December 1, 1927. Serial No. 236,940.

The present invention relates to an improvement in shuttles, and more particularly to automatic weft replenishing shuttles provided with friction tension devices.

In weaving silk and rayon the extreme elasticity of the yarn requires provision to prevent loops forming which sometimes cause yarn breakage.

The object of the present invention is to produce an improved form of thread block for automatic weft replenishing shuttles having a thread tension contributing to the control of the thread in running off from the shuttle. The invention consists in the shuttle herein-
15 after described and particularly defined in the claim.

In the accompanying drawings illustrating the preferred form of the invention, Fig. 1 is a plan of the thread block end of a self-threading shuttle embodying the present invention; Fig. 2 is a front elevation of the same; Fig. 3 is a front elevation of the thread block; Fig. 4 is a front end elevation of the thread block; Fig. 5 is a rear elevation of the thread block; Fig. 6 is a rear end elevation of the thread block; Fig. 7 is a longitudinal vertical section taken on the line 7—7, Fig. 4; and Fig. 8 is a transverse vertical section taken on the line 8—8, Fig. 3.

The illustrated embodiment of the invention is described as follows: The shuttle body 10 has the usual bobbin recess 11 provided, in the case of rayon or silk, with cony fur. The thread block 12 is received in the thread block recess in the shuttle, and it has a table 13, a beak 14, a thread passage 15 and eye 16, all of which occupy the same positions and perform the same functions as is usual in this class of shuttles. So far as the invention is concerned, any form of shuttle having these general characteristics is available for use in connection with the present invention.

The block is provided with a pin 17 located in the passageway from the thread passage to the shuttle eye, and projecting downward in an inclined direction, as shown in Fig. 3, the inclination being such as to permit easy passage of the thread beyond the pin, but to prevent passage outward from it.

Located in the body of the thread block is

a tension slot 18, which receives the tension device indicated in a general way by the reference character 19. This tension device is located on the level of the bottom of the thread passage, and it comprises two tension plates held together by spring pressure. The lower tension plate 20 consists of a flat plate with rounded side edges and a curved lip 21 at the entering end which projects into a hole 22 in the lower part 23 of the thread block. The other end of this tension piece 20 is provided with a hole which receives the reduced end 24 of the screw 25, screwed into the lower part 23 of the thread block. The upper tension member 26 is a similar plate to the first with rounded edges and an upturned lip 27, which projects into the hole 28 in the under side of the upper part 29 of the thread block. The other end of the upper tension plate 26 is provided with a hole which receives the end 24 of the screw 25. A spring-pressed pin 30 is provided with a head which rests on the upper tension plate 26. This pin is encircled by a spring received in the adjusting screw 31, the upper end of which extends to the top of the thread block and affords means for varying the pressure which the spring exerts upon the upper tension member, pressing it against the thread supported by the lower tension member.

The thread block is also provided with an enamel pin 32 located near the inner end of the tension device, see Fig. 7. The shuttle threads up in the usual manner. On the first shot of the shuttle to the left, as viewed in Fig. 1, the thread enters the thread passage and descends into the recess 34 of the shuttle nose, and on the next shot in the opposite direction the thread runs down into the passageway leading from the thread passage to the thread eye and enters between the out-turned lips of the tension device, where it takes up a position as indicated in dotted line in Fig. 1, extending through the thread passage to the glass rod 32, thence at an angle between the members of the tension device to the shuttle eye, where it is discharged between the usual porcelain wear pins 33 of the shuttle.

The tension applied by the device to the

thread may be adjusted by means of the screw 31 to a greater or lesser amount, depending upon the character of the yarn being woven.

In some common forms of tension devices found in self-threading shuttles, the entrance of the thread into the thread passage is resisted by the requirement that the thread should at the same time enter between the members of the tension device. In the present construction there is no impediment to the free entrance of the thread into the thread passage of the thread block, after which, when the thread is thoroughly caught by the block, the thread will be drawn into the tension device. The thread is prevented from escape from the tension device by the pin in the passageway leading from the thread passage to the shuttle eye, and it is drawn over the glass pin at the point where its direction of motion changes from that in line with the thread passage to the direction in which it passes through the shuttle eye, so it is thereby guided over good-wearing parts in its passage from the bobbin to the eye, and prevented from any accidental escape therefrom.

The tension members themselves are identical in form, and this conduces to cheapness and facility of manufacture. Furthermore, when worn to an extent requiring replacement, this is easily accomplished by taking the thread block out of the shuttle and removing first the screw 25, which releases the one pair of ends of the tension members, and then withdrawing the pin 17, which is held in place by friction in the hole in which it is supported, whereupon the two tension members may be turned from the position which they normally occupy in the shuttle, to a position extending outwardly therefrom, with their upturned lips 21 and 27 still remaining in the holes 22 and 28, whereupon, by tipping the upper tension member upward, it may be taken out, and similarly, by tipping the member downward, the latter may be removed and new ones inserted.

Having thus described the invention, what is claimed is:

A shuttle having a thread block provided with a thread passage, a tension device located parallel to the thread passage and in front of the same in the line of the lead of the thread from the thread passage to the shuttle eye, such tension device comprising two horizontal tension members, each provided with upturned side and front end lips, and with holes at the ends opposite the upturned lips, a pin in the shuttle block passing through the holes in the tension members to hold those ends in place, and the block being provided with positioning holes to receive the upturned lips of the other ends of the tension members.

In testimony whereof I have signed my name to this specification.
